UNITED STATES PATENT OFFICE

ELMER M. WACHTEL, OF TWO RIVERS, WISCONSIN, ASSIGNOR TO HAMILTON MANUFACTURING COMPANY, OF TWO RIVERS, WISCONSIN, A CORPORATION OF WISCONSIN

DESIGN FOR AN OPERATING ROOM CABINET OR SIMILAR ARTICLE

Application filed March 16, 1931. Serial No. 39,110. Term of patent 7 years.

To all whom it may concern:

Be it known that I, ELMER M. WACHTEL, a citizen of the United States, residing at Two Rivers, in the county of Manitowoc, State of Wisconsin, have invented a new, original, and ornamental Design for Operating Room Cabinet or Similar Article, of which the following is a specification, reference being had to the accompanying drawing, forming part thereof.

In the drawing, the figure is a perspective view of an operating room cabinet embodying my new design, and showing the cabinet when closed.

I claim:

The ornamental design for an operating room cabinet or similar article substantially as shown.

In witness whereof, I hereunto subscribe my name.

ELMER M. WACHTEL.
